United States Patent Office.

WILLIAM A. FARLEY, OF ST. ANDREW'S BAY, FLORIDA.

Letters Patent No. 95,215, dated September 28, 1869.

IMPROVEMENT IN CONSTRUCTION OF VESSELS.

The Schedule referred to in these Letters Patent and making part of the same.

To all whom it may concern:

Be it known that I, WILLIAM A. FARLEY, of St. Andrew's Bay, in the county of Washington, and State of Florida, have invented a new and useful Improvement in Construction of Vessels; and I do hereby declare that the following is a full, clear, and exact description thereof, which will enable others skilled in the art to make and use the same, reference being had to the accompanying drawings, forming part of this specification.

The object of this invention is to provide a new and improved mode of laying out and ascertaining the form for the hulls of vessels.

The invention consists in producing patterns of two different curves, taken from two radii, the one obtained by taking two-thirds the measurement of the beam of the required vessel, and the other from a radius of one-half the said measurement.

Also, in the use of the said patterns, in a manner to obtain the required curves for any part of the sides and bottom of the vessel by one pattern, all as hereinafter more fully specified.

Figure 1 represents a diagram of a vessel, of the form which it is designed to produce, and

Figure 2 represents a rear and sectional view, showing also the application of the pattern to different parts of the hull.

Similar letters of reference indicate corresponding parts.

I first make a diagram of the plan of the vessel I propose to build, and divide the line of the cross-section at the widest part, as at *a*, into thirds, and take two-thirds the distance as a radius, to form the curve of that part of the pattern for the large circle for the floor-timbers, running one-third the width of the vessel from the keel. I then take one-third the said distance as a radius for the small circle, for the distance from the end of the large circle up to the gunwale. -

In fig. 2, *b* represents the radial line for the large circle from the centre, distant two-thirds the breadth at the line *a*; *c* and *d*, the radius of the small circle from the centre, one-third the said distance.

Taking these two circles so formed and united, I make a pattern, *A*, which, used as represented in fig. 2, gives the shape required at any required point along the sides of the vessel. That is to say, the lower end of the pattern being always taken for the line of the keel, the timbers for any section cut by the pattern, beginning at the lower end thereof, and extending along the pattern as much as required for the distance from the keel to the gunwale, will be the shape required.

For deeper or shallower vessels, the lengths of the radii may be lengthened or shortened, as required. For instance, if a light-draught vessel is required, the floor-circle will be enlarged, and the nuckle-circle will be shortened, and *vice versa*.

The same pattern reversed on the timber, turns the counterwork to make the stern.

Having thus described my invention,

I claim as new, and desire to secure by Letters Patent—

The herein-described mode of producing patterns for shaping the timbers of vessels, substantially as specified.

Also, the improved mode of producing the form required for the vessel, at any part, by means of the improved pattern herein shown and described.

The above specification of my invention signed by me, this 14th day of June, 1869.

WILLIAM A. FARLEY.
